HOWARD H. SMITH, OF TORONTO, OHIO.

PUZZLE.

1,082,460.

Specification of Letters Patent.

Patented Dec. 23, 1913.

Application filed August 30, 1911. Serial No. 646,871.

To all whom it may concern:

Be it known that I, WILLIAM M. BUSHFIELD, a citizen of the United States of America, and resident of Toronto, county of 5 Jefferson, and State of Ohio, have invented certain new and useful Improvements in Puzzles, of which the following is a specification.

This invention relates to a novel form of 10 puzzle, and has for its object the production of a simple and fascinating device wherein a plate or card has provided a diamond-shaped slot from which lead other slots to the various outfield and battery positions assumed by the players of a baseball team and a slot representing the players' bench, and wherein two readily distinguishable sets of playing-pieces, designated "men," each bearing a designating character or symbol, are movably mounted in said slots; the puzzle being to retire the men of 15 the team on the bench to their proper positions in the field and to place the opposing team on the bench.

20 A further object is to provide a puzzle of the character mentioned wherein the positions to be occupied by the various men of the team on the bench are indicated.

The invention resides in the features of 25 construction, arrangement of elements, and combinations of parts which will hereinafter be fully described, reference being had to the accompanying drawings, forming a part of this specification, in which—

30 Figure 1 is a top plan view of the invention with the men of the opposing teams in their proper respective positions; Fig. 2 is a similar view with the men removed, showing the arrangement of the slots; and Figs. 3 and 4 are sections taken respectively on the lines 3—3 and 4—4, Fig. 1.

Referring to said drawings, in which like designating characters distinguish like parts throughout the several views—1 indicates a 35 plate or card which has formed therein a diamond-shaped slot constituting a base-running path, designated generally by the numeral 2, the four sides of which are herein designated 2^a, 2^b, 2^c and 2^d, and which encloses, or marks the limits of, a diamond-shaped panel 3. Leading into said panel 3 from the position of the home-plate 4 is a slot 5 which extends to the position of the pitcher's box, and a slot 6 leads into said 40 panel from the side 2^c to the short-stop's po-

sition. Leading outward from the various angles of the slot 2 are short slots 7, 8, 9 and 10 which respectively represent the positions to be occupied by the catcher and the first, second and third basemen. Also 45 leading outward from the side 2^b to the positions of the left and middle fielders are short slots designated respectively 11 and 12, while a short slot 13 leads from the side 2^b to the position of the right fielder. Located 50 back of the position occupied by the catcher and communicating with the outer end of slot 7 is a slot 14, the same being designed to represent the players' bench or the position of the "at bat" team and extending 55 to the position of the right fielder. Located 55 back of the position occupied by the catcher and communicating with the outer end of slot 7 is a slot 14, the same being designed to represent the players' bench or the position of the "at bat" team and extending 60 to the position of the right fielder. Located 60 back of the position occupied by the catcher and communicating with the outer end of slot 7 is a slot 14, the same being designed to represent the players' bench or the position of the "at bat" team and extending 65 to the position of the right fielder. Located 65 back of the position occupied by the catcher and communicating with the outer end of slot 7 is a slot 14, the same being designed to represent the players' bench or the position of the "at bat" team and extending 70 to the position of the right fielder. Located 70 back of the position occupied by the catcher and communicating with the outer end of slot 7 is a slot 14, the same being designed to represent the players' bench or the position of the "at bat" team and extending 75 to the position of the right fielder. Located 75 back of the position occupied by the catcher and communicating with the outer end of slot 7 is a slot 14, the same being designed to represent the players' bench or the position of the "at bat" team and extending 80 to the position of the right fielder. Located 80 back of the position occupied by the catcher and communicating with the outer end of slot 7 is a slot 14, the same being designed to represent the players' bench or the position of the "at bat" team and extending 85 to the position of the right fielder. Located 85 back of the position occupied by the catcher and communicating with the outer end of slot 7 is a slot 14, the same being designed to represent the players' bench or the position of the "at bat" team and extending 90 to the position of the right fielder. Located 90 back of the position occupied by the catcher and communicating with the outer end of slot 7 is a slot 14, the same being designed to represent the players' bench or the position of the "at bat" team and extending 95 to the position of the right fielder. Located 95 back of the position occupied by the catcher and communicating with the outer end of slot 7 is a slot 14, the same being designed to represent the players' bench or the position of the "at bat" team and extending 100 to the position of the right fielder. Located 100 back of the position occupied by the catcher and communicating with the outer end of slot 7 is a slot 14, the same being designed to represent the players' bench or the position of the "at bat" team and extending 105 to the position of the right fielder. Located 105 back of the position occupied by the catcher and communicating with the outer end of slot 7 is a slot 14, the same being designed to represent the players' bench or the position of the "at bat" team and extending 110 to the position of the right fielder.

The diamond-shaped figure 3 presents sharp angles at each of the three bases, as shown, which serve to prevent a man from 110

passing from one side, as 2^a, of the slot 2 to another side, as 2^b, without first entering the base slot, as slot 8, and thence proceeding in a reversed position. Consequently, when 5 a base is already occupied, no man is permitted to pass such base. No sharp angle or corner is presented by the diamond-shaped figure 3 adjacent to the home plate; thus, a man may be freely passed from the slot 2^a 10 to the slot 2^d, and vice versa, without first entering slot 7. While the opening at the home plate 4 is of relatively large dimension, it is not sufficiently large to permit of the playing pieces being inserted or withdrawn therethrough.

With the exception of the base slots 8, 9 and 10, each of which may be entered by a man traveling in either direction along the slot 2, entrance to none of the branch slots 20 may be had except by a man traveling in a single direction, an angle being formed at one side of the entrance to said slots. For instance, to enter slot 13, a man must travel in a forward direction, while, to enter slot 25 11, a man must travel in a rearward direction, angles 13' and 11' being respectively formed at the entrance to said slots preventing the turning thereinto of a man from the opposite direction. An angle 7' at the outer 30 end of slot 7 prevents a man from passing directly from said slot 7 to the side 2^a of slot 2, and vice versa; and an angle 7'' at the inner end of slot 7 prevents a man from passing directly from said slot 7 to that 35 portion of slot 14 located on the left hand side of said slot, and vice versa.

The plate 1 may be unmounted, if desired, but is preferably mounted in a substantially rectangular receptacle 21, being 40 fixed to the latter in any appropriate manner, as by inwardly turned plate engaging flanges 22 carried by the upturned sides 21^a.

The positions of the different men in the field may be indicated by appropriate characters marked or printed upon the plate or 45 card 1 adjacent to said positions, said characters corresponding with those which are to occupy the indicated positions. In like manner the positions of the men of the "at bat" team on the bench may be indicated.

Access for the men to the slots may be had through a suitably located entrance closed in any suitable manner, as by an inserted piece 23.

55 While the arrangement of angles at the entrance to slots as hereinbefore described is deemed preferable as adding to the difficulty of solving the puzzle, it will be understood that such angles are not necessary and 60 that the arrangement thereof, when used, may be varied; I do not, therefore, desire to limit myself to a device in which such angles are employed. Further, it will be apparent that the arrangement of slots may be varied 65 considerably without departing from the

general spirit or scope of the invention as defined in the appended claims.

Having thus described my invention, what I claim as new, and desire to secure by Letters Patent, is—

70 1. A puzzle comprising a plate having a diamond-shaped slot therein, a plurality of branch slots leading from the first mentioned slot to the positions of the men of a base-ball team in the field, a bench slot having communication with the first mentioned slots, and two distinguishable sets of playing pieces mounted to travel in said slots, each piece bearing a suitable designating character.

75 2. A puzzle comprising a plate having a diamond-shaped slot therein, means supporting the portion of said plate inclosed by said slot, a plurality of branch slots communicating with said diamond-shaped slot 80 and leading to the several field positions of the men of a base-ball team, a bench slot having communication with one of said slots, and two distinguishable sets of playing pieces representing opposing teams, each 85 piece bearing a suitable designating character.

90 3. A puzzle comprising a plate representing a base-ball field and whereon the several field positions of the men of a base-ball team 95 are indicated, a diamond-shaped slot representing a base-running path, base slots at the angles of the diamond-shaped slot and communicating with the latter, branch slots leading to the outfield and battery positions 100 from the diamond-shaped slot, a bench slot, and two distinguishable sets of playing pieces representing the men of opposing teams, the men of each team being severally designated to correspond with said indicated 105 field positions.

110 4. A puzzle comprising a plate representing a base-ball field and whereon the several field positions of the men of a base-ball team are indicated, a diamond-shaped slot representing a base-running path, base slots at the angles of the diamond-shaped slot and communicating with the latter, branch slots leading to the outfield and battery positions 115 from the diamond shaped slot, a bench slot wherein positions for the men of an "at 120 bat" team are indicated, and two distinguishable sets of playing pieces representing the men of opposing teams, the men of each team being severally designated to correspond with the indicated positions.

125 5. A puzzle comprising a plate having the several field positions of the men of a base-ball team indicated thereon, a diamond-shaped slot constituting a base-running path, a plurality of slots leading from said path to the various indicated positions, a bench slot having communication with said path, and two distinguishable sets of playing pieces movable in said slots and repre- 130

senting the men of opposing teams, the men of each team being severally designated to correspond with the indicated field positions.

- 5 6. A puzzle comprising a plate having the several field positions of the men of a baseball team indicated thereon, a diamond-shaped slot constituting a base-running path, a plurality of slots leading from said path to the various indicated positions, a bench slot having communication with said path, and two distinguishable sets of playing pieces movable in said slots and representing the men of opposing teams, the men of each team being severally designated to correspond with the indicated field positions, and angles at the entrances to some of the branch slots whereby access thereto may be had by a man when moving in one particular direction.
- 10 15 of each team being severally designated to correspond with the indicated field positions, each of the slots leading to the basemen's positions and the playing pieces being relatively so formed that the movement of one 20 25 of the latter through the diamond-shaped slot past such base slot is prevented when the latter is occupied.

7. A puzzle comprising a plate having the several field positions of the men of a baseball team indicated thereon, a diamond-shaped slot constituting a base-running path, a plurality of slots leading from said path to the various indicated positions, a bench slot having communication with said path, and two distinguishable sets of playing pieces movable in said slots and representing the men of opposing teams, the men of each team being severally designated to correspond with the indicated field positions, 30 35 the playing pieces designated pitchers and the slot leading to the pitcher's box being relatively so formed that access to the latter by other than the former is prevented.

8. A puzzle comprising a plate having the

several field positions of the men of a baseball team indicated thereon, a diamond-shaped slot constituting a base-running path, a plurality of slots leading from said path to the various indicated positions, a bench slot having communication with said path, two distinguishable sets of playing pieces movable in said slots and representing the men of opposing teams, the men of each team being severally designated to correspond with the indicated field positions, and angles at the entrances to some of the branch slots whereby access thereto may be had by a man when moving in one particular direction.

9. A puzzle comprising a plate having the several field positions of the men of a baseball team indicated thereon, a diamond-shaped slot constituting a base-running path, a plurality of slots leading from said path to the various indicated positions, a bench slot having communication with said path, and two distinguishable sets of playing pieces movable in said slots and representing the men of opposing teams, the men of each team being severally designated to correspond with the indicated field positions, each playing piece comprising a head, a base and a connecting shank, said shank being of less width and greater length than the widths of the various slots whereby the reversal of position of such piece in a slot is prevented.

In testimony whereof I affix my signature in presence of two subscribing witnesses.
